UNITED STATES PATENT OFFICE.

RUFUS A. SIMPSON, OF OAKLAND, CALIFORNIA.

SERVICE BUTTER CUTTER.

Application filed December 7, 1920. Serial No. 428,928.

To all whom it may concern:

Be it known that I, RUFUS A. SIMPSON, a citizen of the United States, residing at the city of Oakland, in the county of Alameda and State of California, have invented certain new and useful Improvements in Service Butter Cutters, of which the following is a specification.

The invention relates to improvements in devices for cutting the small squares or pats of butter which are served with meals in restaurants and like places.

The principal object of my present invention is to provide a machine of this character in which the large block of butter is positively fed forward during the interval when the cutting knife is not in operation. In the several devices now on the market, the butter is fed forward by means of a biting pawl which works very imperfectly due to the fact that the pawl at times becomes gummed with the oil and grease, or the parts become worn and consequently do not properly bite on the feed shaft, resulting in pieces of butter which are not of uniform thickness. My present invention aims to overcome these objections, to provide a feed which is positive in operation and yet which may be varied so as to allow pats of different thickness to be cut.

Another object of the invention is to provide an improved form of knife whereby the pats are not dragged along by the knife as they are cut from the block of butter, and thereby forced into contact with adjacent pieces resulting in the various pats being held together when they drop from the machine, necessitating their being separated by hand.

Another object of the invention is to arrange the knife holding means so that a uniform tension is secured on the knife without regard to the adjustment of the knife holding block. Furthermore the particular form of knife used in my improved device necessitates the same being placed in the holding frame with the cutting edge in its proper position. Therefore I provide the knife and frame with certain means to prevent the knife from being placed in an improper position.

Another object is to provide an improved form of spiral face cam, which permits the feed of the butter to be varied and which may be turned in a reverse direction without damage to the contacting arm.

With these and other objects in view, the invention consists in certain novel features of construction, form and arrangement of parts herein illustrated and more specifically pointed out in the appended claims.

Reference being had to the accompanying drawing forming a part of this specification:

Figure 1 is a view in plan of my improved cutter.

Figure 2 is a view of rear elevation of the same.

Figure 3 is a view in end elevation.

Figure 4 is a view in section on the line 4—4, Figure 1.

Figure 5 is an enlarged view in section showing the end of my butter cutter and the knife in the act of cutting off a pat of butter.

Figure 6 is an enlarged view in elevation of an improved form of a cutter knife and a cutter wire which may be used as a substitute therefor.

Figure 7 is an enlarged cross sectional view of the cutter knife.

Referring to corresponding parts in the several views by the same numerals of reference, my improved cutter consists of a V-shaped body 1, the sides of which are at right angles to each other. This body is provided with a suitable lug 3 on the underside by which it is removably attached to a stand 4. The butter to be cut is in the form of a parallelopiped and this block of butter is pushed forward towards the cutting end of the device by means of the plate 90 or follower block 5. The block of butter is divided longitudinally into four smaller blocks of equal size by means of two cuts at right angles to each other. These cuts are made by the cutting blades 6 which may be formed integrally with the frame 7 or may be separately attached thereto in any preferred manner. The opening 7' in the cutter frame is practically the exact size of the cross section of the prism of butter. The cutter frame 7 is itself attached to the forward end of the body 1 by means of screws 8 which engage suitable lugs 9 formed underneath the sides 2.

At the rear of the cutter frame is formed an upwardly extending bracket 10' having a bearing 10 in which is revolvably mounted a shaft 11. The latter projects outside of the bracket and is there provided with a flat portion 12 for securing the hub of the knife frame 13, and the block 14 to which the cutting blade is secured. This hub and

block are secured by means of set screws 15', and 15. The knife frame comprises the bow shaped spring member 16 to which is attached an operating handle 17. The outer 5 end of this frame is provided with a pin 18, on which is secured one end of the cutting blade, the other end of which blade is secured to pin 19 on the inside of block 14. Between these pins extend the cutting element, two forms of which are shown in 10 Figure 6, the form denoted by 20 being made of wire of high tensile strength by forming a loop 21 on each end.

The other form of knife is denoted by 22 15 and as here shown is provided with holes 23 and 24' the former of which is larger than the latter, and correspondingly the pin 19 is larger than pin 18, making it necessary that the knife be positioned in a correct position 20 with respect to its ends. The blade of this knife is not symmetrical in cross section but comprises a side 24 which is parallel to the direction of movement of the blade as indicated by the arrow in Figure 7, and the surface 25 making an angle to the surface 24, the thicker portion of the blade being at the cutting edge. From this edge denoted by 26 there extends short bevels 26' to meet the surfaces 24 and 25.

30 Being thus constructed it is necessary that the proper side of the knife blade be placed next to the end surface of the cutter frame 7, and for this reason I form a short bent over portion 30 on one end which is turned outwardly from the face 24. The two ends it will be understood have parallel faces. This prevents the angular side 25 from being placed adjacent the cutting surface of the cutter frame. The object of forming the 40 short bevels 26' is so that the pat of butter which is cut from the main block will have a very short length of surface against which it can stick; and the surface 25 being sloped away from the cut surface of the butter pat, 45 does not come in contact therewith, and hence there is little chance of the pat being retained on the knife and carried around as the handle is further rotated. This action being illustrated in Figure 5.

50 It will be noted that the block 14 is provided with a finger 31 which extends under the hub of the knife frame, and that the latter is provided with a bevel surface 32 which is engaged by the screw 33 through the finger 31. When a cutting blade is placed between the pins 18 and 19 and brought into tension by adjusting the set screw 15, this tension tends to cause the block to assume an angular position on the shaft due to the 60 strain being placed on one side of the block. This unequal strain is overcome, and the block maintained in a correct position by engagement of the end of screw 33 with the inclined surface 32, and furthermore if there 65 is any play between the hub and the bearing

10 this inclined surface will prevent movement of the block 14 toward the bearing. Adjustment of the block 14 on the shaft is secured by reason of the elongated slot 34 formed in the said block. Furthermore by 70 reason of the spring construction of the knife frame an excess tension can not be placed on the cutter blade, the tension being limited to that required to bend the 75 spring 16.

The block of butter is fed through the cutting blades 6 during the interval when the cutter knife is not in front of the opening 7'. The mechanism for accomplishing this result is as follows: on the back wall 2 80 is formed a rearwardly extending arm 40 which is provided with a bearing 41 in alignment with the bearing 10. The shaft 11 is revolvably secured in these bearings and between the same is provided with screw 85 threads 42. Pivottally connected to the rear of the follower block 5 is a bracket 43, the upper end of which is provided with spaced arms 44 having openings through which passes the screw thread portion of the 90 shaft 11. Between these arms is a wheel 45, the interior of which is provided with screw threads for engagement with the screw threads 42 and the end faces of the wheel hubs of which fit closely between the bracket 95 arms.

It will be noted that the side corners of the follower block are provided with laterally extending arms 47 which rest on the upper edges of the side walls 2. These arms are so positioned in reference to the edges of the follower block that the inside edges 48 of the latter do not contact with the inner surface of the V-shaped body.

That portion of the shaft 11 which extends rearwardly through the bearing 41 is reduced in section and mounted thereon is a cam 50. The outer periphery of this cam is cylindrical but its axial face is in the form of a spiral; and in a radial plane this face is beveled as shown at 51. The cam is provided with a hub having a longitudinal slot 54 that engages a pin 55 which extends through the shaft. Back of the hub the shaft is screw threaded as at 56, and mounted thereon is a knurled nut 57 by which the cam may be adjusted longitudinally on the shaft. A spring 58 is interposed between the inner face of the cam and a washer 59 at the face of bearing 41, so that when the nut 57 is turned the spring tends to hold the hub of the cam against the nut 57.

Pivottally mounted between the brackets 10 and 41 is a bar 60, the upper edge of which is provided along its entire length with a sharp corner 61 for engagement with the closely spaced notches 62 formed on the outer periphery of the wheel 45. Thus in effect the edge of this bar acts as a pawl to hold the wheel 45 whenever the bar is moved 125 130

in engagement therewith. Movement of the bar is secured through an arm 63 which is attached to the end adjacent the cam. This arm is provided with a downwardly projecting portion 64 on which is a pin for holding a coiled spring 65, the opposite end of which engages the surface of the rear wall 2. Above the bar the arm is bent rearwardly as shown at 66 so that it lies substantially parallel to the axis of the shaft 11. Its end face is beveled as indicated at 68 to conform substantially to the pitch of the spiral of the cam, and also to the bevel of its face.

The bar 60 is provided at the ends with notches 70 that are slightly wider than the width of the wheel 45, the function of these notches being to prevent the action of the pawl whenever the follower block reaches its limits of operation.

20 The operation of the cutter is as follows: The follower block 5 is positioned at the end of the V-shaped trough adjacent the cam, and the prism or the block of butter is placed in the V-shaped trough with its forward end 25 against the cutter frame 7. The nut 57 is then turned to adjust the cam 50 and if desired the slot 54 may be graduated as indicated at 71 in order to indicate approximately the number of pats of butter which 30 will be cut from one pound. Then the blade frame is turned in a clockwise direction rotating the shaft 11 and carrying the knife across the end of the cutter frame 7. Now the cam 50 is so positioned in relation to 35 the knife that just as the cutter blade starts to pass the rearmost corner of the cutter frame opening, the cam picks up the end 68 of arm 63 and thus moves the sharp corner of the bar 60 out of contact with the 40 notches in wheel 45. The bar is held thus until the cutter blade has at least moved entirely across the end of the cutter frame. Thereafter at an interval depending upon 45 the adjustment of the cam, the end 68 drops from the spiral face of the cam permitting the spring 65 to press the point 61 of bar 60 inwardly until it contacts with one of the grooves 62. The entrance of the edge of the bar into a groove prevents rotation of the 50 wheel so that as the handle is further turned, the screw threads 42 will move the wheel endwise. This movement is, by means of the bracket 43 and follower block, transmitted to the prism of butter which is thus forced 55 through the cutter blade 6, where it is cut off on the next rotation of the knife. When the face of the follower block about contacts with the inner edges of the blades 6, the wheel 45 is positioned above the notch 70 adjacent that end of the device. This notch is sufficiently deep that when the bar is oscillated the bottom of the notch does not come into contact with the wheel and hence the latter turns with the shaft instead of 60 being fed forwardly. The same action takes

place at the other end of the bar when the screw is turned in the opposite direction to return the follower block to its rearmost position. The quicker way of running the follower block back is to lift the bar out of contact with the wheel and turn the latter by hand.

It is to permit the reverse movement of the knife frame that I provide the beveled face on the cam and end of arm 66. With these 75 bevels, when the shaft is turned in the wrong direction the arm will be lifted up without injury, whereas with a straight face spiral, the parts would be brought to a stop and if forced some part would be injured.

As here shown the follower block is held on the bracket 43 by means of a prism 72, this allows the bracket to be swung upwardly and the follower block removed for cleaning. At the same time during ordinary 85 operations it is held on the bracket sufficiently that there is little chance of it being accidentally dropped and so bent out of shape.

With this cutter I secure a positive feed, 90 and at the same time can secure any practical variation of feed. The notches 62 being so closely spaced there is no appreciable difference in the feed if the segment of wheel between successive points of contact with 95 the bar varies by a few notches.

By using a cutting knife of predetermined length whether of wire or otherwise, it can be changed much quicker than where it is wound around adjusting pins. Furthermore 100 by the spring construction of the knife frame it can be subjected only to the proper tension. Thus the various features of my invention go to make a device which will give results in the hands of inexperienced operators, the 105 machine being as near as possible fool proof in its operation and adjustments.

I claim as new and wish to cover by Letters Patent:—

1. In combination with a body having 110 angularly disposed side walls, a cutter frame having crossed blades, a knife frame revolvable about an axis perpendicular to the face of said cutter frame, an adjusting block, a knife having one end secured to said block 115 and the other end to the outer part of said knife frame.

2. In combination with a body for holding a block of butter, a cutter frame having crossed blades for longitudinally dividing 120 said block of butter, a knife frame comprising a hub, a bow shaped arm extending therefrom, said frame being rotatable about an axis perpendicular to the face of said cutter frame, an adjusting block adjacent 125 said hub, and a cutting knife attached to said adjusting block and the outer end of said spring arm.

3. In combination with a V-shaped body, a cutter frame at one end thereof, a shaft 130

5 rotatable in an axis perpendicular to the face of said cutter frame an adjusting block 65 radially movable on said shaft and having one face substantially in the plane of the 70 face of said cutter frame, a knife frame attached to said shaft outside of said block, a spring arm having an outer end substantially in the plane of the outer face of said cutter frame, a pin projecting from said 75 adjusting block and from the outer end of said spring arm, and a cutting knife extending between said pins.

10 4. In combination with a V-shaped body, a cutter frame at one end thereof, a shaft 80 rotatable in an axis perpendicular to the face of said cutter frame, an adjusting block radially movable on said shaft and having 85 one face substantially in the plane of the face of said cutter frame, a knife frame attached to said shaft outside of said block, a spring arm having an outer end substantially in the plane of the outer face of said cutter frame, a pin projecting from said 90 adjusting block and from the outer end of said spring arm, a cutting knife extending between said pins, a face on said knife adjacent to said cutter frame and parallel thereto, an opposite face at an angle to the aforesaid face, said knife having its thicker portion 95 at the cutting edge, and short oblique faces extending from a line to said angular faces to form the cutting edge.

15 5. In a butter cutter, a guide, a cutter frame at one end thereof, means for intermittently feeding the butter through said frame, a knife movable across the face of said frame, said knife comprising a side surface parallel to the face of said frame, an opposite side at an angle to the aforesaid side and a cutting edge formed on the thicker side of said knife.

20 6. In a butter cutter, a guide for the block of butter, a cutter frame for dividing the butter longitudinally, a knife blade adapted 100 to be moved across the face of said frame, said blade having side surfaces converging rearwardly, and a cutting angle on the forward edge.

25 7. In a butter cutter, a guide for the butter, a cutter frame at one end thereof, means for intermittently moving the butter through said frame, a knife blade adapted 105 to be moved across the face of said frame, said blade having short beveled surfaces at the cutting edge, and long beveled surfaces at the rear edge.

30 8. A butter cutter comprising a body forming a guide for a block of butter, a shaft revolvably mounted in bearings at the 110 end of said body, a knife frame attached to said shaft, a knife carried by said frame and movable across the face of said cutter frame, screw threads on said shaft between 115 said bearings, a wheel in threaded engage-

ment with said shaft, said wheel having 65 closely spaced notches around its periphery, a bracket having arms embracing opposite sides of said wheel, a follower block carried by said bracket, a pawl for engaging the notches of said wheel and cam means on said 70 shaft for varying the time which said pawl engages said wheel.

9. A butter cutter comprising a body 75 forming a butter guide, a follower block movable therein and supported only along the upper edges of said body, a screw threaded shaft extending parallel to said body, a bracket slidable on said shaft and having 80 said follower block pivotally connected to the lower end thereof, a wheel in threaded engagement with said shaft, means on said bracket engaging said wheel, and means for allowing said wheel to rotate with said shaft at times.

10. A butter cutter comprising a body 85 forming a butter guide, a follower block movable therein, a revolvable screw threaded shaft extending parallel to said body, a member in screw threaded engagement therewith, a bracket having arms contacting with opposite sides of said member and connected to said follower block, and variable means for intermittently permitting said member to rotate with said shaft at 90 times and to hold it nonrotatable thereon at 95 other times.

11. A butter cutter comprising a body forming a butter guide, a follower block movable therein, a revolvable screw threaded shaft extending parallel to said body, a 100 member in screw threaded engagement therewith, a bracket having arms contacting with opposite sides of said member and connected to said follower block, a cam on said shaft, and means operable by said cam for holding said member non-rotatable at times and allowing it to rotate with said shaft at other times.

12. A butter cutter comprising a body 110 forming a butter guide, a follower block movable therein, a revolvable screw threaded shaft extending parallel to said body, a member in screw threaded engagement therewith, a bracket having arms contacting with opposite sides of said member and connected to said follower block, means for holding said member non-rotatable at times, and an adjustable cam on said shaft for operating said holding means and varying the interval thereof.

13. A butter cutter comprising a body forming a guide for a block of butter, a follower block for moving the butter in said guide, a screw threaded shaft extending longitudinally of said body, a member in 125 threaded engagement therewith, means connecting said member with said follower block and means whereby a relative rotative

movement between said member and shaft takes place during a variable interval.

14. A butter cutter comprising a body forming a guide for a block of butter, a follower block in said guide for moving said block of butter, a screw threaded shaft extending longitudinally of said body, a member in threaded engagement therewith, means connecting said member with said follower block, means for causing a relative rotative movement between said shaft and said member and means for varying the interval of such relative movement.

15. A butter cutter comprising a body forming a guide for a block of butter, a follower block in said guide for moving said block of butter, a screw threaded shaft extending longitudinally of said body, a wheel in threaded engagement with said shaft, said 20 wheel having closely spaced notches on its peripherical surface, means connecting said wheel with said follower block, an oscillative pawl extending parallel to said shaft, a spiral faced cam on said shaft, and an arm 25 engaging the periphery of said cam and connected to said pawl.

16. A butter cutter comprising a body forming a guide for a block of butter, a follower block in said guide for moving said 30 block of butter, a screw threaded shaft extending longitudinally of said body, a wheel in threaded engagement with said shaft, a bracket having said follower block attached thereto and having arms embracing opposite 35 sides of said wheel, an oscillatable pawl for

engaging the periphery of said wheel, a cam axially adjustable on said shaft, a spiral end face on said cam, an arm on said pawl and extending axially to contact with the periphery of said cam, and beveled faces on 40 said arm and said spiral cam.

17. A butter cutter comprising a body forming a guide for a block of butter, a follower block for moving said butter, a continuous rotating screw carrying and moving 45 said block, and means for rendering said block inoperative at times.

18. A butter cutter comprising a body forming a guide for a block of butter, a follower block for moving said butter, a continuous 50 rotating screw carrying and moving said block, a cam on said screw for varying the interval during which said block is operative.

19. A butter cutter comprising a body 55 forming a guide for a block of butter, a cutting frame, a revolvable shaft, means actuated by said shaft for feeding the butter through said frame, an adjusting block on said shaft, a knife frame, a hub thereon, an 60 inclined surface on the inside of said hub, a finger extending from said adjusting block across said inclined surface, a screw in threaded engagement with said finger and contacting with said inclined surface, and a 65 cutting knife extending between said block and said knife frame.

In testimony whereof I affix my signature.

RUFUS A. SIMPSON.
